UNITED STATES PATENT OFFICE.

ALFRED J. EGGAN, OF CHICAGO, ILLINOIS.

SOAP CONTAINER.

Application filed May 5, 1925. Serial No. 28,162.

This invention relates to a container for lard, greases, lubricants, liquid or jellied soft soaps, or for any other article for which it is found applicable, and the invention has for 5 its object to provide, in a manner as herein-after set forth, a container having a normally impervious sealed body portion to prevent leakage or discharge of the contents thereof under normal conditions and capable 10 of being rendered pervious, when occasion requires, on the application of heat or hot water thereto whereby the contents of the body portion can discharge therefrom by percolation to provide a filtering or feeding 15 action therefor.

A further object of the invention is to provide, in a manner as hereinafter set forth, a container including a flexible porous body portion having an impervious coating 20 soluble on the application of heat or water thereto to permit of the discharge of the contents of said body portion by percolation automatically or when pressure is applied thereto.

25 Further objects of the invention are to provide, in a manner as hereinafter set forth, a container for the purpose referred to, which is simple in its construction and arrangement, strong, compact, durable, 30 thoroughly efficient and convenient in use, and inexpensive to manufacture.

With the foregoing and other objects in view, the invention consists of the novel construction, combination, and arrangement of 35 parts, as hereinafter more specifically described and illustrated in the accompanying drawings, wherein is shown an embodiment of the invention, but it is to be understood that changes, variations and modifications 40 can be resorted to which fall within the scope of the claims hereunto appended.

In the drawings wherein like reference characters denote corresponding parts throughout the several views:—

45 Figure 1 is a perspective view of a container in accordance with this invention.

Figure 2 is a vertical sectional view.

Referring to the drawings in detail, the container is illustrated by way of example 50 as of rectangular contour, but it is to be understood that the container can be of any shape desired.

The body portion of the container is indicated at 1 and is formed from woolen, cotton, linen, or silk fabric. As shown, by way of example, the body portion 1 is of the

open-top type, and has the opposed sides and ends at the upper portion thereof secured together as at 2 for the purpose of closing the body portion 1 completely.

60 The body portion 1 is provided with an impervious coating 3 formed from paraffine which will liquefy on the application of heat at and above 30° C. so that the coating will dissolve, thereby rendering the body portion 65 of the container pervious to act as a filter or feeder of the substance contained therein, such as greases, lubricants, liquid or jellied soft soaps. The coating is extended throughout the body portion 1 as well as over the 70 joint formed by the row of stitching 2.

The construction herein referred to provides a container having a normally sealed body portion to prevent leakage or discharge 75 of the contents thereof, and which is capable of being rendered pervious, when occasion requires, on the application of heat thereto, whereby the contents of the body portion can discharge therefrom by percolating to 80 provide a filtering or straining action. The coating 3 is of any desirable thickness, and under normal conditions prevents any possibility of leakage or discharge of the contents of the body portion until it is desired to use such contents. As the coating liquefies, the 85 contents of the body portion 1 can automatically feed therefrom, or if desired, the discharge of the contents can be had quickly by 90 pressure or a squeezing action on the body portion.

In connection with the use of the container for green soap, that is to say soft or jellied soaps, the container is filled with the soap and after the coating has liquefied, the container will act as a feeding device, feeding 95 the amount desired through the interstices of the fabric, retaining the balance for future use, as the soap will become hard and fill the interstices of the fabric, and what will be necessary to do when a further feed is required is to wet the periphery of the container and a feeding action can be had. After the necessary amount of soap has been used, the interstices of the fabric will then be closed by the dried portions of the soap with 100 in said interstices and the container is then stored for future use of its contents.

105 It is thought the many advantages of a container, in accordance with this invention, can be readily understood, although the preferred embodiment of the invention is as illustrated and described, yet changes in the

details of construction can be had which will fall within the scope of the invention as claimed.

What I claim is:—

- 5 As a new article of manufacture, jellied soft soap contained in a permanently closed holder coated throughout with paraffin wax to normally maintain said holder impervi-

ous, said coating liquefiable on the application of heat thereto, said holder formed of 10 textile fabric of sufficient permeability to act as a feeder for the jellied soft soap when the coating has become liquefied.

In testimony whereof, I affix my signature hereto.

ALFRED J. EGGAN.
